UNITED STATES PATENT OFFICE.

GEORGE ANDREW MOLIQUE, OF WOOD RIVER, ILLINOIS.

STEAM TRAP.

1,427,116.

Specification of Letters Patent. Patented Aug. 29, 1922.

Application filed May 13, 1921. Serial No. 469,283.

To all whom it may concern:

Be it known that I, GEORGE A. MOLIQUE, a citizen of the United States, and a resident of Wood River, in the county of Madison 5 and the State of Illinois, have invented certain new and useful Improvements in Steam Traps, of which the following is a specification.

This invention relates to steam traps especially adapted for use in connection with a system of steam pipes.

An important object of this invention is to provide a steam trap having novel means whereby the discharge valve of the same is 15 automatically and quickly operated to expel the water upon being condensed.

The invention further aims to provide novel means whereby the discharge valve is held in its elevated position until the water 20 contained within the bowl is entirely discharged and which when seated will effectively prevent the leakage of the condensation of steam.

A further object of the invention is to 25 provide a steam trap which is entirely automatic in its operation and, which by reason of the arrangement of parts, is not likely to get out of order.

Other objects and advantages of the invention will be apparent during the course 30 of the following description.

In the accompanying drawings forming a part of this application and in which like numerals are employed to designate like 35 parts throughout the same,

Figure 1 is a vertical sectional view through the improved steam trap.

Figure 2 is a horizontal sectional view through the same, the view being taken on 40 line 2—2 of Figure 1.

Figure 3 is a fragmentary perspective of the operating means for the discharge valve of the trap.

In the drawings wherein for the purpose of illustration is shown a preferred embodiment of the invention, the numeral 5 designates a bowl mounted upon a base 6 and secured thereto by means of fastening devices in the nature of screw bolts 7. An 45 inlet pipe may be connected to the upper portion of the bowl and conducts the steam to the bowl where it is condensed. The base or bottom 6 is provided with a discharge pipe 9 which carries off the condensation of steam when the valve is au-

tomatically elevated due to the rise of the water within the bowl.

As illustrated in Figure 1, a standard 10 is arranged vertically within the bowl and is provided at a point adjacent its lower 60 end with ears 11 to which the forked ends 12 of an arm 13 are pivotally connected. The forward end of the arm 13 is provided with a spherical float 14 which rises and descends with the water contained within the 65 bowl. A link 16 is adjustably connected to the arm 13 by means of a collar 17 which is secured in an adjusted position on the arm by means of a set screw 18. By adjusting the collar 17 along the arm 13 the 70 throw of the link 16 may be regulated. However, the inward movement of the collar 17 is limited by means of a coupling 20 which connects the forked ends 12 to the arm 13. As the water within the bowl rises the float 75 14 of course is elevated thereby imparting a corresponding movement to the link 16. As the arm 13 partakes of a vertical movement, the link 16 is swung to a limited extent on the pivot element 22 which passes 80 through ears 23 formed at the lower end of the link 16 and the upper side of the collar 17.

As the arm 13 moves upwardly the link 16 is elevated whereby a pin 25 carried by one 85 branch 26 of a bell crank generally designated by the numeral 27 is engaged with the lower end wall of a slot 28 formed in the upper portion of the link 16 and extending longitudinally of the same. When the lower 90 end wall of the slot 28 contacts with the pin 25 the bell crank 27 is swung on its pivot 29 in a clockwise direction until the weight 30 carried by the other branch of the bell crank passes the vertical plane of the pivot element 29. When the weight 30 passes the vertical center of the pivot 29 it moves downwardly in a clockwise direction by force of 95 gravity and thereby elevates a valve stem 33. The upper end of the valve stem 33 has pivotal connection with a short link 34 provided in its upper portion with a longitudinal slot 36 which receives a pin 38 carried by the intermediate portion of the branch 26. With reference to Figure 3, it will be observed that 100 the branch 26 is comprised of a pair of spaced parallel arms or sides which constitute guides for the link 34 and the upper portion of the link 16.

When the weight 30 is swung by force of 110

gravity in a clockwise direction, the pin 38 is elevated so as to engage the upper end wall of the slot 36 whereby the stem 30 is elevated. This, of course, occurs only after the water reaches a predetermined level and no movement is imparted to the stem until the water reaches such level.

The lower end of the stem 33 is provided with a valve 40 which seats upon a valve seat 41 formed immediately above the outlet pipe 9.

The upward movement of the stem 33 and the movement of the balance weight 30 in a clockwise direction is limited by means of 15 a stop element 46 secured on the stem and adapted to engage a combined guide and stationary stop element 47 which slidably receives the stem. The collar 46 may be adjusted on the stem 33 by means of a set screw 20 50 so that the elevation of the stem may be regulated.

As the float 14 rises the link 16 is elevated and as the float 14 approaches the limit of its upward movement the lower end wall of the slot 28 is engaged with the pin 25 for elevating the branch 26 and consequently the balance weight 30. This initial movement of the branch 26 imparts no movement to the stem 33 and consequently the valve 40 remains seated.

However, when the balance weight 30 passes the vertical plane of the pivot 29 the branch 26 is swung rapidly in a clockwise direction for unseating the valve.

35 As the water level recedes the link 16 is moved downwardly for returning the bell crank gradually to its original position. As the bell crank is returned the stem 33 is held in its elevated position by contact with a ball
40 56 pressed into engagement with the stem by means of a coil spring 58. The pressure exerted by the spring 58 may be varied by means of an adjusting screw 60 threaded into an opening in the standard. When the float
45 14 reaches the limit of its downward movement the pin 38 engages the lower end of the slot 36 for promptly returning the valve 40 to its seat. When thus seated leakage of steam from the trap is absolutely prevented.
50 It will be observed that the weight of the member 30 constantly bears on the valve 40 when the latter is seated, whereby the discharge opening is effectively closed.

Having thus fully described my invention
55 what I claim is:—

1. A steam trap comprising a standard, a valve having a stem slidably associated with the standard, a float having a pivoted arm, a link adjustably connected to said arm and having its upper end formed with a slot, a bell-crank having a branch provided with a pin slidable in said slot whereby the upward movement of said link engages the lower end of said slot with said pin for operating said bell-crank, a second link connected to said

stem and having a slot, a second pin connected to said branch and slidable within said slot, and a weight connected to said bell-crank for elevating the valve.

2. A steam trap comprising a standard, a valve having a stem slidably associated with the standard, a float having a pivoted arm, a link adjustably connected to said arm and having its upper end formed with a slot, a bell-crank having a branch provided with a pin slidable in said slot whereby the upward movement of said link engages the lower end of said slot with said pin for operating said bell-crank, a second link connected to said stem and having a slot, a second pin connected to said branch and slidable within said slot, a weight connected to said bell-crank for elevating the valve, and means associated with said stem for holding the stem in its elevated position until the bell-crank completes its return movement. 70 75 80 85 90

3. A steam trap comprising a standard, a valve having a stem slidably associated with the standard, a float having a pivoted arm, a link adjustably connected to said arm and having its upper end formed with a slot, a bell-crank having a branch provided with a pin slidable in said slot whereby the upward movement of said link engages the lower end of said slot with said pin for operating said bell-crank, a second link connected to said stem and having a slot, a second pin connected to said branch and slidably within said slot, a weight connected to said bell-crank for elevating the valve, and a stop element for limiting the vertical movement of said stem. 90 95 100

4. A steam trap comprising a standard, having a guide constituting a stop element, a valve having a stem slideable through said guide, a collar adjustable on said stem and adapted to engage said stop element whereby the vertical movement of said valve is limited, a crank connected to said standard and having a branch, means connecting said branch to said stem, said crank being provided with a second branch having a weight, a float having an arm, a link connected to said arm and having a slotted connection with the first named branch of said crank for moving the crank when the float reaches a predetermined level, and means to secure said valve in an elevated position until the crank completes its return movement.

105
110
115

5. A steam trap comprising a support, a float pivoted to said support and having an arm, a link having a collar adjustably secured on said arm and having its upper portion formed with a longitudinal slot, a lever pivoted to the upper portion of said support and having a branch provided with a pin slideable in said slot, a guide carried by said support, a valve having a stem passed through said guide, a link pivoted to the upper end of said stem and having a longi- 130

tudinal slot, a pin connected to said branch and extended into said second named slot for elevating the second named link when the float reaches a predetermined level, said 5 lever being provided with a second branch having a weight normally arranged at one side of the vertical center and adapted to be swung to the other side of the vertical center of said support when the lever is

swung on its pivot, a stop element adjustably secured on said stem and adapted to engage said guide to limit the upward movement of said stem, a tensioning spring having means engaging said stem to secure the same in an elevated position until the lever completes 15 its return movement and means to adjust said tensioning means.

GEORGE ANDREW MOLIQUE.
